CLAIM

The ornamental design for a retractable leash with integrated waste bag dispenser, as shown and described.

DESCRIPTION

FIG. 1 is a top, front, left side perspective view of a retractable leash with integrated waste bag dispenser, showing my design;

FIG. 2 is a rear, left side perspective view thereof;

FIG. 3 is a front, left side perspective view thereof;

FIG. 4 is a bottom, left side perspective view thereof;

FIG. 5 is a left side view thereof;

FIG. 6 is a right side view thereof;

FIG. 7 is a front view thereof;

FIG. 8 is a rear view thereof;

FIG. 9 is a top view thereof; and,

FIG. 10 is a bottom view thereof.

The broken line showing of environmental structure forms no part of the claimed design.

1 Claim, 8 Drawing Sheets
